UNITED STATES PATENT OFFICE

CHARLES MILLER AND LEO SHOLTZ, OF NEW YORK, N. Y.

DESIGN FOR A SHOE

Application filed September 4, 1931. Serial No. 41,021. Term of patent 3½ years.

To all whom it may concern:

Be it known that we, CHARLES MILLER and LEO SHOLTZ, both citizens of the United States, and residents of the city of New York, county of New York, and State of New York, have invented a new, original, and ornamental Design for a Shoe, of which the following is a specification, reference being had to the accompanying drawings, forming part thereof.

Figure 1 is a perspective view of one side of the shoe having mainly bright-finish or glossy material, such as patent leather; and

Figure 2 is a perspective view of the other

side of the shoe having mainly dull-finish material, such as suede.

The dominant feature of the design is a shoe having one side mainly of dull-finish material, such as suede, and the opposite side mainly of bright-finish or glossy material, such as patent leather.

I claim:

The ornamental design for a shoe, or similar article substantially as shown and described.

CHARLES MILLER
LEO SHOLTZ.
